ADSORBER

Ernest B. Miller, Baltimore, Md., assignor, by
mesne assignments, to Chester F. Hockley, Re-
ceiver for The Silica Gel Corporation, Balti-
more, Md., a corporation of Maryland

Application November 13, 1930
Serial No. 495,474

8 Claims. (Cl. 183—4)

This invention relates to adsorbers and more particularly to adsorbers for the removal of gaseous or vaporous constituents from mixtures of gases or mixtures of gases and vapors.

5 It is a general object of the present invention to provide novel and improved forms of adsorbents and adsorber assemblies.

More particularly, it is an object of the invention to provide adsorbers wherein granular, adsorbent material is arranged in suitable beds interposed as barriers between opposite ends of a casing in such a manner that all of the gaseous mixture passing from one end of the casing to the other must pass through a bed of adsorbent material.

15 Among the important features of the invention may be enumerated the following:

A. The arrangement of the adsorber bed or beds to provide a maximum area exposed to the 20 gas mixtures in a chamber of minimum size.

B. The provision for arranging a group of adsorbers into a battery.

C. The unique manner of constructing the adsorbers and appurtenances wherein the end walls 25 thereof are formed by towers each including portions of ducts adapted to communicate with the interior of the adsorber casing.

D. The construction of the adsorber casings wherein the valves controlling communication 30 between inlet and outlet ducts and the interior of the casing cooperate directly with the walls of the casings.

Other and further features and objects of the invention will be more apparent to those skilled 35 in the art upon a consideration of the accompanying drawings and following specification wherein are disclosed several exemplary embodiments and assemblies of adsorbers constructed according to the present invention. It is to be 40 explicitly understood that various and sundry deviations may be made from the accompanying disclosure, and that combinations of the features of the various modifications can be made without departing from the spirit of the invention so long 45 as these departures fall within the scope of the appended claims.

In said drawings:

Figure 1 is a vertical, longitudinal, central section through an adsorber constructed according 50 to one form of this invention;

Figure 2 is a horizontal section taken on line 2—2 of Figure 1 and showing two adsorbers forming part of a battery;

Figure 3 is a transverse vertical section taken 55 on line 3—3 of Figure 2;

Figure 4 is a view similar to Figure 2, showing, however, but a single adsorber wherein the arrangement of the adsorber beds is in the form of a W instead of a V as in Figure 2 and wherein two valves associate each duct with the casing; 60

Figure 5 is a vertical section similar to Figure 1 through a modified form of adsorber wherein the adsorber beds are horizontal instead of vertical as in the previously disclosed forms;

Figure 6 is a horizontal section through a further modification of the invention wherein the adsorbers are arranged in a plurality of horizontal beds grouped in banks; and 65

Figure 7 is a vertical section taken on line 7—7 of Figure 6. 70

The present invention deals particularly with adsorbers for handling large quantities of mixed gases or gases and vapors. Primarily the adsorbers are intended for removing moisture from air but in no sense is the invention intended to 75 be limited to this use for obviously the same construction and arrangement would be available for a great variety of uses. The adsorbers are intended to handle large quantities of gases and to impart the minimum frictional resistance thereto. 80

For a clear understanding of one type of apparatus in which such adsorbers may be used, reference may be had to my copending application Serial No. 425,883, for Adsorption system, wherein the use of adsorbers in banks is clearly 85 disclosed. In that invention it is pointed out that several adsorbers are required in order to obtain continuous operation. One or more adsorbers are always in use for adsorbing and may be connected in series or in multiple. At least one 90 adsorber is always on the activation cycle or is being cooled subsequent to activation and in some cases a separate cooling phase is provided requiring an additional adsorber.

While the adsorbers may be used with any 95 available adsorbent material it is preferred that the material be granular silica gel of any suitable size and of the type manufactured by The Silica Gel Corporation of Baltimore, Maryland. This material is available in hard, porous granules and is extremely satisfactory in that it can be subject to high temperatures for activating or reviving without any appreciable deterioration and because it neither swells nor changes its size, shape or other physical characteristics when saturated with condensed vapors. Furthermore, it is substantially inert chemically. 100

The adsorbers of the present invention are constructed so that the gas or air to be treated is passed through them from end to end and the 110

treated air then withdrawn. The use of one adsorber is continued until the adsorbent reaches the desired degree of saturation, when the stream of untreated gas is diverted to a second adsorber 5 and that containing the saturated adsorbent is put on the activation phase.

Conveniently, activation is accomplished by directly passing heated products of combustion through the adsorbents and for this purpose a 10 fluid fuel is preferable. For the purpose of cooling an adsorber, a closed circuit may be effected between the heated adsorber and a suitable air cooler, for instance, in the form of a surface condenser and air circulated in this closed circuit 15 until the adsorbent material therein is reduced to a sufficiently low temperature to be in a condition for further adsorption.

In order that the various phases and cycles above enumerated may be conducted most economically, it is necessary to have a plurality of 20 ducts for inlet and discharge purposes for each adsorber, for instance, each adsorber requires an inlet duct for the untreated gas, and a discharge duct for the stripped gas; an inlet duct for the hot activating gases and a discharge duct for conveying the spent activating gases to a stack; an inlet duct for the cooling gas and an outlet duct for the cooling gas. In the event that two 25 or more adsorbents are to be used in series and advanced in their position in the series as their saturation increases, then an additional pair of ducts is required for each added stage in the adsorption cycle.

A careful perusal of the drawings and accompanying description of the various forms of adsorbents contemplated by this invention will lead to a full understanding of the provisions for accomplishing the above enumerated features.

Referring now particularly to Figures 1, 2 and 40 3, there is disclosed a type of adsorber in which a casing 10, substantially in the form of a hollow, rectangular parallelepipedon contains the adsorbing elements generally indicated at 11. This casing has a closed top 12, a closed bottom 13 and side walls 14 and 14', preferably formed of sheet metal with suitable heat insulation backing and reinforced where necessary by suitable structural steel shapes.

The front and rear or end walls of the adsorber are formed, respectively, by one wall of each of the towers 15 and 16. These towers are substantially identical and each comprises a plurality of sections 17, 18, 19 and 20 of horizontal ducts which sections are superimposed and may have the common, horizontal dividing walls 21, 55 22 and 23. Each tower is constructed and adapted to be assembled as a unit and its inner end wall 24 closes one end of the adsorber casing. This end wall 24 is perforated by a plurality of 60 ports, one for each duct section and each provided with a combination nozzle and valve seat 26 preferably rectangular in shape. This reinforces the edges of the port opening through the wall 24 and provides a seat for the valve disc 27 65 which controls communication between the corresponding duct section of the tower and the interior of the adsorber casing. Such valves are clearly disclosed in my copending application Serial No. 483,847, for Damper valves. In that application the valves are shown as comprising discs 27 universally mounted on a stem 28 extending across the duct and entering a cylinder 29 containing a suitable piston which can be moved in either direction by means of a suitable 70 expanding medium as, for instance, compressed

air, for the purpose of closing and opening the valve as desired. The inner end of the valve stem 28 is guided on suitable antifriction rollers 30 carried on brackets 31 from the nozzle and seat member 26.

Each valve operating cylinder 29 has a tubular extension 32 provided with a ball end freely mounted between plates 33 carried by the wall of the duct opposite the port, to permit universal movement of the operating mechanism. By providing each duct and thus the tower with integral valve assemblies, the towers can be constructed complete with the valves and operating mechanism and assembled against the ends of the adsorbers.

Since the adsorbents are intended to be used in banks or batteries with adjacent sides abutting, it is possible to make the abutting walls of adjacent adsorber casings, for instance, the wall 14, 90 serve the dual purpose of a side wall for two casings. The towers are formed of the full width of the adsorber casings so that when the towers of adjacent casings are in position they can be secured together so that the duct sections form continuations of each other.

Each adsorber, it will be noted, is so constructed that the inlet ducts are at one end and the outlet ducts at another so that any gas in passing through the casing must move from one end thereof to the opposite end.

To insure that this gas come intimately into contact with the adsorbent material, it is interposed as a relatively thin bed or layer between opposite ends of the casing. In the form shown in Figures 1, 2 and 3 there are two beds 35 which 100 are identical. They are each formed between a pair of vertical, parallel screens 36. The screens may be made of woven metal fabric or suitably perforated sheet metal or similar material and should have meshes or openings of smaller size 105 than the minimum size of the granules of the adsorbent material contained between the screens. As clearly seen in Figure 1, the screens are provided with vertical reinforcing strips 38 suitably formed of angle iron or the like and 110 horizontal reinforcing members 39 similarly formed. These reinforcing members form a coarse grid over the screen to prevent bulging from the weight of the adsorbent and the pressure of the gas passing therethrough. The vertical reinforcing strips 38 on the two screens forming one adsorber bed are disposed in staggered relation as seen in Figure 2 preferably with those on one screen centered between the 115 two on the opposite screen. In this manner if 120 there is any bulging of the screen material due to the weight of the adsorbent material, the whole screen will assume a rather sinuous section of substantially uniform thickness so that the air resistance throughout the area will be 125 substantially the same, whereas if the reinforcing members were opposite each other the sections between them would remain thin and the intermediate sections would increase in thickness, thereby increasing the resistance and decreasing the flow of air through these portions 130 so that all of the adsorbent material would not be used effectively. The screens extend fully 135 from the bottom to the top of the casing and are suitably attached to these places in an air-tight 140 manner.

Each bed or layer of adsorbent material has its median plane vertical and the planes of the two beds in each adsorber converge. At one end the beds are spaced apart substantially the 145 50

full width of the adsorber casing and at the other end they are substantially together. To prevent air leakage by the beds, the vertical ends of the beds are closed by the plates 40 having their 5 edges suitably connected to the screens as at 41. At the spaced ends of the beds, a metal sheet 42 connects each plate 40 to the adjacent end wall 24 and at the end where the beds are close together the plates 40 are connected by angles 10 43 and a connecting sheet 44. This connecting sheet 44 is perforated for the passage of the ends of the valve stems 28 and to prevent leakage at these points the closed end cylinders 45 are tightly secured to the periphery of the openings 15 and for reinforcement may be tied together as by the strap 46. The cylinders 45 permit the working of the valve stems through the sheet 44 without permitting any leakage and without requiring stuffing boxes or packing which is 20 inconvenient to use at the high temperatures existing during activation.

By arranging the adsorber beds in a V formation, a maximum exposed area to both the inlet and the discharge gases is provided, since each 25 of the beds has an area substantially equivalent to that of a side wall 14 of the casing and the combined areas of the beds are very much greater than the cross-sectional area of the casing. In this manner the resistance to flow 30 in the adsorber can be reduced to a point where it is less than the resistance to flow through the ducts and valve ports so that it can be considered that the adsorbers introduce substantially 35 no additional retardation to the flow of gases therethrough.

For convenience in introducing the adsorbent material 50 between the screens 36, the top wall of each adsorber just above the beds is fitted with 40 a plurality of tubes 51 extending into the space between the screens 36 and these tubes are provided with suitable removable caps 52 whereby the material can be introduced and the caps then closed. The strips or reinforcing members 53 fitting against the top wall 12 of the casing insure that there be no passage of gas above the level of the material in the adsorbers even though there be some slight shrinkage thereof. Such shrinkage will occur during the early use of adsorbers as the result of settling and the cracking of the adsorbent material from the heat and additional make-up material can be added from time to time until equilibrium is established.

In Figure 4 the construction is similar to that 55 described in connection with Figures 1, 2 and 3 but where large volumes of gas are to be handled it is desirable to introduce additional valves between the ducts and the adsorber casings and this figure shows two valves 55 controlling the 60 flow from each duct section 56. These valves are of similar construction to those previously described and are carried by the duct sections which form parts of similar towers. Where such great gas flow is required through the adsorbers, 65 additional exposed area of adsorber bed is desirable and for that purpose there are four adsorber beds 57 instead of two as in Figures 1, 2 and 3. These beds are arranged in the form of a W as viewed in plan.

In this form of construction, the end plates 70 40 of contiguous ends of adsorber beds are connected by plates 58 and the two remaining ends, at the top of the W, are connected as at 59 to the side walls of the casing although they could 75 equally as well be secured to the end walls.

In the form of construction illustrated in Figure 5 the adsorbent material is arranged in horizontal beds instead of in vertical beds and in this type of construction no care need be taken to insure that the beds are initially completely filled with adsorbent nor no effort need be made to keep them entirely filled since shrinkage of the material will not open a passageway for the gases to by-pass the bed. The casings, towers, ducts and valve construction in this form may be identical with that in the forms already described, the only difference existing in the disposition and construction of the adsorber beds. Each bed is defined as in previous forms by the parallel, spaced screens 60 arranged horizontally and between which the adsorbent material 61 is placed. The ends of the beds are closed by the vertical plates 62, and a plurality of beds are arranged in spaced superposed position supported by the angle bars 63 suitably attached to their end plates.

In order that the full area of but one side of each bed be exposed to each end of the adsorber casing, the inclined baffles 65 are provided. Where these are between beds, their one end is secured 100 to the lower edge of one of the end plates 62 of the upper bed and to the upper edge of the end plate 62 of the next lower bed but at the opposite end of the bed. The sides of the plates 65 have an air-tight connection with the side walls of the 105 casing. The upper and lower plates 65, of course, are secured at one of their ends to the upper and lower walls, respectively, of the casing. These baffles or plates not only insure that the gases pass through the beds rather than over them but in a 110 sense direct the gases to pass substantially vertically through the beds. This form of construction provides an enormous exposed area of adsorber bed within a restricted space and prevents any possibility of leakage due to shrinkage of the 115 adsorbent material. As viewed in Figure 5, it is preferred to have the inlet ports at the left in order that the gases being treated pass downwardly through the adsorbent material and do not tend to lift it and cause channeling.

As a further modification of the arrangement of the adsorber beds, Figures 6 and 7 illustrated another form intended for large gas flow in which, as seen in Figure 6, two or more valves 70 are provided at each end of the adsorber for each of the 120 ducts 71 whereby large flow can be effected. It will be noted from this drawing that the ducts are much larger in proportion than in the other forms in order that sufficient flow can be effected 125 without material frictional resistance. Within the 130 casing 72 are arranged in a V formation similar to that of Figure 2, the two adsorber assemblies 73, associated with each other and the casing for gas tightness in substantially the same way as are the beds in Figure 2. These adsorber assemblies, however, are not simple beds of adsorbent but each comprises a plurality of horizontal beds 75, as clearly seen in Figure 7. Each one of the assemblies 73 may be likened to the 135 arrangement of adsorber beds in Figure 5. The screens 76 forming the top and bottom members of each bed 75 are supported between the solid end plates 77 and at appropriate intervals along the sides their solid edge plates 78 are secured to 140 vertical angle members 79 supporting them from the bottom 80 of the casing.

Between the individual beds of adsorbent are arranged the inclined baffle plates 81, disposed in the same relationship as the baffles 65 in Figure 5. 150

The edges of these baffles are secured to the end plates 77.

The construction just described partakes of the beneficial features of the modifications disclosed in Figures 1, 2 and 3 and in Figure 5 for the inclined arrangement of the assemblies increases the total exposed area which is further augmented by the horizontal, superposed arrangement of the individual beds of each assembly. This construction is not subject to difficulties resulting from settling of the adsorbent material in the beds. It permits the use of thin layers of adsorbent material each of relatively small area which insures no loss in efficiency due to unequal thicknesses of the adsorbent. Due to the relatively small size of each adsorbent unit, i. e. each bed and its supporting components, the construction is relatively light and cheap and any replacements require only small low-priced parts.

Each of the modifications described includes the essential features of forming the end walls of the casing by parts of the tower and duct assemblies and includes the arrangement of the valves to seat directly in the end walls and to be carried by the ducts and towers. Each of the forms permits the exposed area of adsorbent material to be many times that of the cross-sectional area of the adsorber casing and each permits the adsorbents to be composed of a plurality of relatively small units. The material advantages to be gained from these novel features will be readily appreciated by those skilled in the art.

Having thus described the invention, what is claimed as new and desired to be secured by Letters Patent is:—

1. In an adsorber, in combination, a casing having a closed top, bottom, and sides, adsorbent material in said casing, means closing opposite ends of said casing and comprising walls of a plurality of superposed gas ducts, and valve parts cooperating with said walls to control the flow of gas to and from said adsorbent to each of the ducts.

2. In an adsorber, in combination, a closed casing, means providing inlet and outlet ports for said casing, means separating the said ports and including adsorbent material, said adsorbent material being arranged in vertical beds at an angle to each other and to the line of movement of gases through the adsorber, each bed being confined between perforated vertical sheets, spaced reinforcing members on the outside of each sheet, the members on the two sheets for each bed being staggered for the purpose described.

3. In an adsorber, in combination, a closed casing, inlet and outlet ports in the end walls thereof, vertically disposed adsorber beds in said casing, each bed being disposed between spaced vertical screens, vertical reinforcing bars for the

outside of each screen, the bars on the two screens of each bed being staggered, said beds being arranged in a pair in V-formation with the open side of the V facing one end and the closed side the other, and means to insure that all gases passing from one end to the other of said casing must pass through the beds.

4. In an adsorber system, in combination, a bank of contiguous closed casings, superposed ducts extending along the ends of the bank of casings and contiguous thereto, a port connecting each casing individually to each duct, a valve for each port, and an adsorber bed in each casing interposed between the ends thereof to be traversed by gas passing through the casing.

5. In an adsorber system, in combination, a plurality of casings of rectangular cross section banked with their corresponding sides in abutment, a tower closing each end of each casing and including a section of each of a plurality of horizontal gas ducts, a port for each duct section, and a valve for each port to control the flow between its duct and the corresponding casing, means connecting the towers on corresponding ends of the casings into continuous horizontal ducts, and adsorbent material in each casing.

6. An adsorber including, in combination, a casing, top, bottom, and side walls therefor, a barrier of adsorbent material between the ends of said casing, a tower at each end of the casing, each tower including a wall closing the casing end, and a plurality of duct sections, each of said tower walls having a port therethrough for each duct.

7. An adsorber including, in combination, a casing, top, bottom, and side walls therefor, a barrier of adsorbent material between the ends of said casing, a tower at each end of the casing, each tower including a wall closing the casing end and a plurality of duct sections, and a valve for each duct section, said valve cooperating with a seat and port in the tower wall which closes the casing.

8. In an adsorber, in combination, a horizontal casing having ends, one end having an inlet port and the other an outlet port, a vertical barrier between the ends of said casing and including a plurality of banks of adsorber trays, said banks being at an angle to each other and to the direction of passage of gas through said casing, each bank comprising a plurality of superposed, horizontal trays spaced apart vertically, closed sides and a perforate bottom for each tray, a plate connecting the upper edge of one side of each tray to the opposite lower edge of the tray above whereby gas passing said bank must pass the perforate tray bottoms, and a layer of dry, porous, adsorbent material in each tray.

ERNEST B. MILLER. 135
